WALTER H. RUDOLPH, OF NEW YORK, N. Y.

COMPRESSOR

Application filed January 27, 1928. Serial No. 249,793.

This invention relates to pumps or compressors such as are employed for pumping fluid either in liquid or gaseous form. The principal object of the present invention is to provide a portable, light weight compressor, having a relatively high capacity or output for its size and weight.

Another object is to provide a compressor in which all the moving parts thereof are symmetrically disposed about a common axis of rotation, thereby to secure a perfectly balanced vibrationless device which will give a substantially uniform fluid delivery, free from surging or impulses and which consequently will not require the use of a storage, or pressure equalizing, tank.

A further object is to provide a compressor in which there are no valves to stick, click or leak, no connecting rods, no belts or driving chains, or no gears to hum or rattle.

Another object is to provide a compressor which will be adjustable to secure outputs of various maximum pressures.

A further object is to provide a device of the character to which this invention relates that will be self-cooling, self-oiling, dust-proof, rustproof and leakproof.

Another object is to construct a compressor capable of being directly connected to high speed motors, engines, or other power sources without requiring the use of speed reduction gears or similar devices.

A further object is to provide a compressor of marked simplicity of construction, capable of being manufactured and sold at a relatively low cost, while at the same time being of such sturdy construction that the maintenance cost thereof will be reduced to a minimum.

Another object is to provide a compressor which is effectively sealed both at the piston ends and about the valve means so that escape of gases is effectually prevented and therefore the compressor will be particularly applicable for use in mechanical refrigeration or for the compression of dangerous gases.

The above and other objects of the invention, such as to provide a compressor in which there is a minimum clearance and therefore high pumping efficiency and also in which

there is an extensive radiating surface and therefore high thermal efficiency, will appear more fully from the following more detailed description and by reference to the accompanying drawings forming a part hereof, wherein Fig. 1 is a central longitudinal section taken on the line 1—1 of Fig. 2, partly in elevation and partly broken away, of a compressor constructed in accordance with the principles of my invention; Fig. 2 is a section on the line 2—2 of Fig. 1; Fig. 3 is a section on the line 3—3 of Fig. 1; Fig. 4 is a section on the line 4—4 of Fig. 3; Fig. 5 is a plan view of the valve which governs the entrance and exit of the fluid being pumped; Fig. 6 is a side elevation of the valve shown in Fig. 5; Fig. 7 is a section on the line 7—7 of Fig. 5; Fig. 8 is a sectional detail of the coupling for connecting the compressor shaft to a driving element such as an electric motor, this figure being a vertical section taken on substantially the same line as the section of Fig. 1 but showing the parts which comprise the coupling in a partially separated condition in order to show more clearly in the construction of such parts; Fig. 9 is a section on the line 9—9 of Fig. 8; Fig. 10 is a side elevation of the end of a cylinder and piston, this view being taken substantially on the line 10—10 of Fig. 2; Fig. 11 is a section taken on the line 11—11 of Fig. 5 and showing in addition to the valve of Fig. 5 a portion of the spindle which fits over said valve, and Fig. 12 is a detail plan taken on the line 12—12 of Fig. 11.

In order that the more detailed description presently to be given will be better understood, the construction and operation of the compressor will first be briefly described. It consists of a cylinder block mounted for rotation within a casing about a central axis. This block comprises a plurality of cylinders extending radially from said axis and in each of which is slidably mounted a compressor piston. The cylinder block is rotated preferably at a high speed by any suitable means, such for example, as an electric motor preferably connected directly to the cylinder block or a part integral therewith. The inner end of each cylinder is provided with a port or aperture which is adapted to communicate

during the rotation of the cylinder block with suitably arranged intake and delivery ports of a valve member held against rotation by suitable securing devices interposed between 5 it and the outer casing and said valve member is located at the center of the casing, so that as the cylinder block is rotated, each cylinder will be placed alternately in communication with said intake and delivery 10 ports. The reciprocation of the pistons is brought about by the effect of the centrifugal force produced as a result of the rotation and by the action of a circular cam race, arranged eccentrically to the axis of rotation of the 15 cylinder block, the centrifugal force causing the pistons to move outwardly and perform a suction stroke while the cam race engages the outer ends of the pistons, or any suitable nonfriction member carried thereby, to periodically urge the pistons inwardly to perform 20 their compression strokes.

As shown most clearly in Fig. 1 of the drawings, a satisfactory constructional example of the invention comprises an outer 25 casing consisting of a lower casing member 10 and upper casing member 11. These members are preferably constructed of aluminium in order to reduce the weight of the compressor to a minimum and also to obtain the 30 advantage of the high heat conductivity of this metal and thereby secure a maximum cooling of the device. The upper and lower casing members 10 and 11 are connected together, adjacent to their peripheries, by any 35 suitable means, such as the bolts 12, and define a fluid tight oil chamber 13. The lower casing member 10 is provided with a pair of radially extending conduits 14, 15, which in the particular example illustrated, extend 40 substantially at right angles to each other and terminate at their outer ends at the periphery of the casing. The conduit 14 is the delivery conduit and the conduit 15 is the suction conduit. At their inner ends the conduits 14, 15 communicate respectively with the vertically extending conduits 16, 17 provided in a valve member 18 which seats upon a disc 19, preferably of steel, secured to the casing member as by headed screws 19^a, the 45 heads of which project upwardly into recesses 18^a in the valve member. The top surface of said valve member is substantially spherical in configuration for a purpose to be hereinafter more fully set forth and the conduit 16 terminates at its upper end, in a port 20 provided in said top surface. The conduit 17 communicates with a port 21 also formed in the top of the valve member.

The main driving shaft or spindle 22 of 50 the compressor is a relatively short member having in the bottom thereof a central bore or recess 23, the shape or configuration of which is similar to that of the valve member 18 so that said bore and said member 18 will 55 be in neat running fit engagement.

Secured to the spindle 22 is a cylinder block 24 which is shaped to provide a plurality of equally spaced, radially extending, cylinders 25 arranged about the axis of rotation of the spindle and block. The cylinder block 24 is 60 preferably secured to the spindle 22 by a shrink fit so as to produce a structure in which the block and spindle are substantially integral. The spindle 22 is enlarged at the lower end thereof and said enlargement is 65 provided with a plurality of radially extending substantially conical bores 26 which communicate at their inner ends through apertures or ports 26^a provided in the spindle with the central bore 23 of said spindle. 70 There is one bore 26 for each cylinder 25 and each bore 26 at its outer end is of the same diameter as the bore of each cylinder 25 and is in communication at said outer end with its respective cylinder. 75

Mounted within each of the cylinders 25 is a piston 27, the inner end of which is partially conical in configuration as indicated by the reference character 28 to conform with the conical bore 26 and which is also partially 80 spherical in configuration as indicated by the reference character 29. The purpose of providing the pistons at their inner ends with the conical and spherical portions is to eliminate dead air spaces or pockets and thereby reduce 85 clearance space to an irreducible minimum. At the outer end thereof, each piston 27 has mounted therein a roller 30. Each roller 30 is rotatably mounted upon a pin 31, one end 90 of said pin being secured against rotation within its respective piston by means of a small pin 32. The periphery of each of the rollers 30 as shown is concaved for interengagement with the convex inner surface of a race 33. Obviously the rollers could be convex and the surface of the race concave or any other construction could be employed in which the rollers and race so interengage that the rotation of the pistons about their central 95 axes is prevented. 100

The race 33 is of circular formation and is seated within a groove preferably formed by counterboring the meeting faces of the upper and lower casing members 11 and 10 respectively; the inner surface of the race being 105 eccentrically disposed relatively to the axis of rotation of the cylinder block. The extent of eccentricity of the race relatively to the axis of rotation of the spindle 22 and cylinder block is such that the stroke of the pistons 110 within the cylinders is substantially as shown by the relative positions of the pistons at the right and left hand sides of Fig. 1 of the drawings. 115

For the purpose of permitting the compressor 120 to be adjusted for securing various maximum pressures, means are provided for varying the extent of the stroke of the pistons. This is accomplished by locating the axis of rotation eccentric relatively to the center of 125 130

- the circular bottom of the groove in which the race 33 is seated, the bore of the boss 11^b being bored eccentric to the groove counterbore of the upper casing member 11. The inner and outer surfaces of the race while circular are also eccentric. The amount of eccentricity of the centers of the race groove and the inner and outer surfaces may be varied as desired in accordance with the requirements; 5 the radius lines X, Y, Z shown in Fig. 2 show by way of example the principles of construction, the center of the radius X coincides with the axis of rotation, while the centers of Y and Z indicate the relative positions of the parts shown in the drawings. It will be noted that, as shown, the centers of the radii Y and Z for the inner and outer surfaces of the race are located on a line extending perpendicular to a diameter which passes 10 through the centers of X and Y. If now the race is rotated within its groove to bring the center of Z in said diameter but between the centers of Y and X the strokes of the pistons will be reduced by an amount equal to twice 15 the eccentricity of Z—Y while if the race is rotated to bring the center of Z as far as possible from the center of X the strokes of the pistons are increased. Obviously any desired adjustment of the pistons' strokes, 20 within the limits just described, may be obtained by moving the race to positions within such limits. It will be apparent that a condition of no stroke of pistons may be obtained by making the eccentricity of Y, Z, equal to that 25 of Y, X so that the center of the inner surface of the race may be brought into coincidence with the axis of rotation. Any suitable means may be provided for the convenient rotational adjustment of the race, as shown, the 30 race is provided on its outer surface with worm gear teeth 33^a with which meshes a worm 33^b secured to a shaft 33^c, said shaft being suitably journaled in the lower casing member and projecting outwardly thereof; 35 the outer projecting end of the shaft being provided with any well known means for rotating it. Rotation of the race, when it is used as a gasket to seal the meeting joints of the casing member, would be accomplished by 40 first loosening the bolts 12. If however it is desired to have the race so that it can be rotated without loosening of the bolts, a gasket between the casing members obviously could be employed. 45 In the ordinary operation of the compressor the centrifugal force, due to the rotation of the cylinder block, will maintain the concave peripheries of the rollers 30 in engagement with the cooperating convex inner 50 face of the race 33, thereby holding the piston in a position such that the spherical portion 29 of the inner end thereof will be properly located with respect to the spherical upper face of the valve 18. In order to insure that 55 the pistons will not be jarred out of their proper positions of alignment, for example when the compressor is moved bodily while inoperative, the outer end of each cylinder has secured therein a small pin 35; said pin being fixed in a small apertured boss 36 projecting laterally from the outer upper end of each cylinder 24. The outer end of each pin 35 is bent downwardly across the outer face of its respective cylinder and projects into a longitudinally extending groove 37 provided 60 in the outer wall of each piston. It will be noted that the pins 31 project into said grooves 37 and each projecting end of each pin is also provided with a groove which is in alignment with the groove 37 of the piston. From the above described construction it will be seen that should the pistons move inwardly so as to bring the concave periphery of the rollers 30 out of contact with the race 33, the pins 35 will serve to keep the pistons in 65 their proper positions of alignment. In the ordinary operation of the compressor, the rollers 30 however are held by the centrifugal force in engagement with the race 33 so that no strain is placed upon the pins 35. 70 For the purpose of connecting the rotatable cylinder block to any suitable driving means and preferably to an electric motor such as shown in the drawings, the following coupling construction is provided: The upper reduced end of the spindle 22 is threaded and has engaged thereon an annular coupling lock nut 40. Before the nut 40 is secured upon the spindle, a threaded coupling sleeve 41 is 75 placed upon the upper reduced end of the spindle. The sleeve 41, as clearly shown in Figs. 1 and 8 of the drawings, is provided at its lower end with a flange 41^a which surrounds the upper end of the spindle loosely and is adapted to engage under the lower 80 face of the nut 40 after the latter has been secured in position upon the spindle. The upper face of the spindle 22 is provided with coupling jaws 22^a, as shown most clearly in Fig. 8, and the coupling lock nut 40 is provided with similar jaws 40^a which are brought into alignment with the jaws 22^a when the nut 40 is screwed home into position. The upper reduced end of the spindle 22 is provided with a bore 42 in which is 85 adapted to be received the armature shaft 43 of the motor M. Said armature shaft has secured thereto, preferably by a press fit, a lock jaw ring 44, the outer periphery of which is threaded to be engaged by the inner 90 threaded upper end of the coupling sleeve 41. At its lower end the coupling jaw ring 44 is provided with coupling jaws 44^a adapted to engage in the recesses provided between the jaws 22^a and 40^a of the spindle 22 and nut 40 respectively. 95 The partition wall 11^a of the casing member 11 is provided at the center thereof with a boss 11^b. Seated within this boss is a bushing 45 preferably of steel or other suitable 100

material, having good wearing qualities and having at the bottom thereof a lateral flange 45^a. Interposed between the bushing 45 and the outer periphery of the upper reduced end 5 of the spindle 22 and seated upon a shoulder formed at the junction of the enlarged lower end and the upper reduced end of the spindle 22 is a ball bearing 46. Confined between the upper face of the ball bearing 46 and a 10 cup-shaped packing cup 47 is a coiled compression spring 48 which serves to exert through the ball bearing a predetermined pressure for holding the inner spherical surface of the bore 23 of spindle 22 in engagement with the upper spherical surface of the 15 valve member 18. Confined between the packing cup 47 and a bearing cap 49 is a packing gasket or washer 50 constructed of felt or other suitable material. At its outer edge 20 the cap 49 is provided with a depending flange 49^a, the inner surface of which is provided with screw threads for engagement with cooperating screw threads cut in the upper end of the bushing 45. It will be noted 25 that the packing members 47, 49 and 50 form, in effect a stuffing box which prevents gas leakage from the compartment 13. When the cap 49 is screwed down tight, the bushing 45 is clamped rigidly to the boss 11^b by pressure 30 exerted on the lower surface of the boss 11^b by the flange 45^a of bushing 45 and on the upper surface of boss 11^b by the lower surface of flange 49^a.

35 A cooling fan 51 is suitably secured to the armature shaft 43 for the purpose of causing a continuous current of cooling air to be drawn across the top surface of the partition wall 11^a, the upper casing member 11 above the partition wall 11^a being provided with a 40 plurality of air admission openings 52 spaced about the periphery of the vertical wall of said casing and establishing communication between the outside air and the compartment defined by said casing member 11 above the 45 partition wall 11^a. Immediately above the openings 52 the inner vertical wall of the casing member 11 is provided with a projecting rib 53 which is grooved or recessed as indicated by the reference character 54. A 50 dished baffle plate 55 has pivotally mounted upon the peripheral flange 55^a thereof, a plurality of eccentric lock or latch members 56, said members being secured to said flange 55^a by means of the headed rivets 57. Each 55 latch member has a boss portion 56^a through which the rivets 57 pass and a handle portion 56^b by means of which each latch may be turned upon its respective rivet. The rivets 57, as clearly shown in Fig. 3, are located eccentrically of the boss portion 56^a of the latches 56 so that when the latches are 60 turned upon said rivets, the eccentric throw of the boss portion 56^a can be moved into and out of engagement with the annular groove 65 54. At its central portion the dished plate

55 has an aperture 58 of sufficient diameter to clear the outer circumference of the boss 11^b so that when the latches 56 are disengaged, the baffle plate 55 may be moved to the dotted line position shown in Fig. 1 of the drawings. 70

Immediately adjacent to the partition wall 11^a and also to its outer vertical wall, the upper casing member 11 is provided with a plurality of bosses 59 arranged at spaced intervals about the casing member and provided with threaded apertures into which are adapted to be received the lower ends of the connecting bolts 60 which serve to clamp the motor M securely in engagement with the compressor unit. 80

The manner in which the parts so far described are assembled is substantially as follows: The rollers 30 are placed within the outer hollow ends of the pistons 27 and the pins 31 are inserted into the central bearing bore of the rollers 30 and through the aligned apertures provided for their reception in the walls of the pistons. The pins 32 are inserted into the holes drilled for their reception in the piston wall and pins 31 after which the inner end of the pins 32 are bent upwardly to the position shown in Fig. 1 of the drawings, this being done by the insertion of a punch or the like into the small aperture 61 provided in the lower part of the piston wall. The pistons 27 are then inserted into the assembly formed by the cylinder block and spindle 22, it being understood that the cylinder block has been shrunk fit upon the lower enlarged end of the spindle. The pins 35 are then inserted into their bosses 36 and are locked in position by bending the inner ends of said pins upwardly and the outer ends thereof downwardly, it being understood that the downwardly bent outer end of each pin will be of sufficient length to project into the longitudinally extending groove 37 of its respective piston but out of contact with the bottom wall of said groove. The valve 18 having been placed in position within the lower casing member 10, the cylinder block and spindle assembly, with the pistons mounted therein, is placed in the lower casing member with the bore 23 of the spindle 22 engaged over the valve 18. All of the pistons 27 are moved to their innermost limits of travel and the race 22 is then placed in position within the half groove formed in the lower casing. The ball bearing 46 is then placed over the upper reduced end of the spindle 22 after which the coupling sleeve 41 is slipped over the spindle. The lock nut 40 is then screwed home upon the spindle so as to bring the jaws 40^a thereof into conterminous relationship with the jaws 22^a of the 125 spindle. The upper casing member 11 with the bushing 45 contained therein is then placed in position and the bolts 12 are inserted and screwed home to clamp the two casing sections together. The compression 130

spring 48, the packing cup 47, the packing washer 50 are placed in position in the order mentioned and the bearing cap 49 is screwed onto the bushing 45 until its lower surface is tight against the upper surface of the boss 11^b. The dished baffle plate 55 is placed within the upper casing member 11 in the dotted line position shown in Fig. 1. The fan 51 and coupling jaw ring 44 are secured to the armature shaft 43 of the motor M and the lower projecting end of the armature shaft 43 is inserted into the bore 42 of the spindle. When the coupling jaw ring comes into contact with the upper end of the coupling sleeve 41, said sleeve is rotated to cause the threads thereof to engage with the threads of the coupling jaw ring 44 and to draw said ring towards the upper end of the spindle. It will be understood that as the armature shaft is inserted into the bore 42 and lowered into position, the jaws 44^a will be brought to a position that will insure their meshing with the jaws 22^a and 40^a of the spindle 22 and lock nut 40 respectively and that during the operation of screwing the coupling sleeve upon the coupling jaw ring the armature shaft will be held against rotation. In order to guard against the formation of an air cushion between the lower end of the armature shaft 43 and the bottom of the bore 42 the spindle 22 is provided with a small hole 62 leading from the bottom of said bore 42. After the coupling sleeve 41 has been screwed home to clamp the jaws 44^a, 22^a and 40^a in proper intermeshing relationship, the dished baffle plate 55 is then raised to its upper position and the latches 56 are rotated into engagement with the annular groove 54 to lock the baffle plate in its operative position. After this has been done the motor casing with the field magnets secured thereto is placed upon the upper casing member 11 and the bolts 60 are inserted and screwed home to hold the motor and compressor parts in assembled condition.

Means are provided for securing a continuous circulation of oil about and through the moving parts of the device, said oil acting not only to lubricate the bearing surfaces, but also as a cooling fluid. The compartment 13 defined by the upper and lower casing members is maintained partially filled with oil and advantage is taken of the fact that the cylinder block rotating at a high speed can be utilized as a pump for causing the oil within said compartment 13 to be circulated to and about the frictional bearing surfaces of the moving parts of the compressor. In order to secure this result, a rib 63 extends radially of the partition wall 11^a from the boss 11^b to the outer vertical wall of the upper casing member 11; said rib is drilled to provide an oil conduit 64, the outer end of which is closed by a block 65. Communication between the conduit 64 and

the compartment 13 is established through the small vertical conduit 66 which it will be noted communicates with the compartment 13 immediately adjacent to the inner peripheral wall thereof, the region adjacent to said inner wall being, as will be readily understood, the zone of greatest pressure due to the effect of centrifugal force upon the fluid. At its inner end the conduit 64 communicates with the space above the ball bearing 46 by means of a vertically extending groove 67 formed in the inner wall of the boss 11^b which leads to a peripheral oil conduit 67^a formed in the outer wall of said bushing and with which communicates a plurality of holes 68 drilled through the wall of the bushing 45. The oil pumped through the conduits 66, 64, groove 67 and holes 68 passes through the ball bearing 46 and circulates back to the compartment 13. In order to provide a free passage for the oil from the ball bearing back to the compartment, the upper face of the enlarged lower end of the spindle 22 is slightly turned down or faced off to provide a clearance space indicated by the reference character 69.

Lubrication of the cooperating bearing surfaces of the spindle 22 and valve member 18 is effected by means of a conduit 70 formed in the lower wall of the lower casing member 10 and extending radially of said wall. At its outer end the conduit 70 terminates in a recess 70^a; said recess is closed by a plug 71 and said recess communicates with the interior of the compartment 13 adjacent to the inner face of the peripheral wall through a hole 72. Oil may be poured into compartment 13 by laying the compressor on its side with the recess 70^a turned up, removing the plug 71 and pouring oil into said recess, from whence it will flow into compartment 13 through hole 72. To drain oil from the compartment 13 the plug 71 is removed and the compressor is laid on its side with the recess 70^a down. At its inner end the conduit 70 communicates with a vertically extending oil conduit 73 provided in the valve member 18. The upper end of the conduit 73 of the valve member 18 terminates at the middle of the spherical surface formed on the upper face 11^a of said valve member, the oil being pumped under pressure by the centrifugal force through the hole 72 and conduits 70, 73 to lubricate the spherical bearing surface. In order to prevent the lubricating oil from being forced into the cylinders 24, a circular groove 74 is formed in the inner spherical surface of the bore 23 of the spindle 22, said groove surrounding the exit end of the oil conduit 73 and being located between said exit end and the ports 26^a in the spindle. One or more vertically extending grooves 75 are formed in the inner end of the bore 23 of the spindle and extend from the circular groove 74 thereof between adjacent ports of said

spindle to a point below said apertures to conduct the oil from the groove to the cylindrical portion of the bearing surfaces between the bore of the spindle and the valve member 18.

Lubrication of the contacting bearing surfaces of the pins 31 and rollers 30 is provided by the following means: Each piston 27 has drilled therein a hole 76 which furnishes communication between the hollow interior of the piston and the longitudinally extending groove 37 with which the pin 35 cooperates. The grooved end of the pin 31 which projects into the groove 37 is provided with an axial hole 77 extending into the pin to a point between the side edges of the roller 30. Said axial hole communicates with the inner end of a radial hole 78 in said pin and the outer end of said radial hole leads into an oil groove 79 formed in the periphery of the pin and extending preferably longitudinally thereof.

As the pressure set up in the oil adjacent to the circumferential bounding wall of the compartment 13 will normally be in excess of the gas pressure, means are provided for reducing the oil flow to the spherical surface of the valve member 18 in case there should be a tendency of the oil to be forced by such pressure past the circular groove 74 into the inner ends of the cylinders. Such means comprises a wick 80 of any suitable compressible material placed in the conduit 70. A plate 81 movable transversely of said conduit by a screw 82 engages the wick 80 and serves to compress it. Adjustment of the amount of pressure exerted by the plate on the wick will vary the rate of oil flow through the conduit accordingly. The plate 81 is seated in a recess in the conduit and the recess and plate are so dimensioned that the latter forms a seal for preventing oil leakage around the screw 82.

The operation of the device is as follows: Assuming the parts have been assembled as hereinbefore described and that the compartment 13 has been filled with oil, rotation of the motor M will cause its armature shaft, through the intermeshed jaw construction of the coupling members, to drive the cylinder block. Owing to the centrifugal force set up, the hollow pistons 27 will be urged outwardly of the cylinders 24 so that the rollers 30 carried by the outer ends of the pistons will be held into engagement with the race 33. The race 33 as hereinbefore described, while circular, is eccentric to the axis of rotation of the cylinder block by an amount sufficient to cause the pistons when forced to their innermost positions by the race to move approximately into engagement with the inner cone-shaped ends of the cylinders, the pistons being forced inwardly to perform their compression stroke by the eccentricity of the cam race, and said pistons being moved outwardly to perform their suction stroke preferably solely

by the influence of the centrifugal force. As the spindle and cylinder block rotates, the ports 26^a in the spindle at the inner ends of the cylinders will be brought alternately into registry with the ports 20 and 21. As the cylinder block rotates, the piston will be actuated by the centrifugal force due to the angular velocity of the cylinder block and will consequently be forced outwardly thus holding the roller 30 in engagement with the race 33 and the co-action of the race and roller restraining the outward travel of the piston. Just as the piston begins its outward travel the port 26^a at the inner end of the cylinder is open to the port 21 and the communication between such ports is maintained open until the piston has reached the end of its outward stroke. The port 21 being connected through the conduits 17 and 15 to the outside atmosphere or to a fluid containing reservoir air or fluid is drawn into the cylinder to fill the space vacated by the receding piston. After the piston has reached its outermost limit of travel it is, upon further rotation of the cylinder block, forced inwardly by the pressure of the roller on the race. As will be noted by referring to Fig. 5 of the drawings, each cylinder will rotate through an angle of approximately 90° after the piston has begun its travel inwardly before the port 20 is uncovered. During this time the air or gas is being compressed and therefore as the port 20 is uncovered the fluid will be ejected under pressure through the port 20 and conduit 16 to the discharge conduit 14.

During the rotation of the cylinder block the oil contained in the compartment 13 is caused to be circulated in the manner hereinbefore described, the oil for lubricating the ball bearing 45 being taken from the zone of greatest pressure through the conduits 66 and the oil for lubricating the cooperating bearing surface of the valve member 18 and 22 also being taken from the zone of greatest pressure and being delivered in both cases to a point relatively near the axis of rotation at which point the pressure due to centrifugal force is much lower than in the region adjacent to the periphery of the compartment 13; it will thus be seen that a continuous circulation of the oil under pressure is assured. The delivery of the oil under pressure between the spherical bearing surfaces bounded by the circular groove 74 results in the maintenance of a film of oil in this region under sufficient pressure to act as a cushion which very effectively takes up the end thrust due to the weight of the motor armature and the pressure of the spring 48.

Cooling of the compressor is effected in two ways, first by the contact of the outside atmosphere with the outer walls of the casing members which define the compartment 13 and second by utilizing the cooling air which is also circulated through the motor M by the fan 51.

Air is drawn in by the fan 51 through the openings 52 in the vertical wall of the upper casing member 11 and is caused to be deflected downwardly by the lower surface of the inclined wall of the dished baffle plate 55 thereby to sweep across the upper face of the partition wall 11^b which forms the upper wall of the compartment 13. The air then passes upwardly through the aperture 58 and is driven outwardly by the fan and is deflected by the upper surface of the inclined baffle wall to pass upwardly through the motor about the field coils and armature and thence outwardly through openings provided in the top of the motor casing. Owing to the fact that the compartment 13 is well filled with oil, the heat of compression is transmitted to the body of oil and through such body to the aluminum walls of the casing members which define the lower compartment. Likewise such heat as may be generated by the frictional contact of the moving parts is also absorbed by the oil and transmitted to the aluminum casing.

It will be seen that as every moving part of a compressor constructed in accordance with the principles of my invention moves in a perfect circle and that as every unit of mass which moves has an exact counterpart diametrically opposite on the orbit of rotation, there are no unbalanced centrifugal forces, and that, as none of the moving parts have a rubbing velocity at, or near, the tangential velocity of the periphery of the cylinders, or in excess of accepted safe limits, the compressor may be actuated at a very high speed which speed is high enough to maintain the piston rollers in contact with the race under all conditions encountered in operation of the compressor solely and entirely by the centrifugal force developed. The compressor unit may therefore be directly connected to a high speed electric motor without the employment of any speed reduction gears. Although the construction permits high speed operation and under certain circumstances such high speed will be preferred, it will be understood that the invention is not limited to high speed operation but that the principles of construction and operation are equally adapted for low speed rotations. In the latter case, if necessary, springs or the like may be employed to supplement the centrifugal forces for holding the piston rollers against the race.

It will also be noted that all the rotating surfaces of the moving parts are abundantly and efficiently lubricated by a body of oil which also functions as a cooling fluid. There is a total absence of poppet valves, connecting rods, gear, chains, belts and links, such as are employed in compressors as heretofore constructed and the use of which necessarily limits the speed by reasons of sudden reversals in their directions of travel, unbalanced forces, and consequent excessive vibra-

tion, inertia and excess noise and wear at high speed.

It will furthermore be noted that no radial bearings are employed except those of the prime mover. Only a single stationary valve, namely, the valve member 18, is employed, which member performs the function of twelve moving valves. The mounting of the valve member 18 so that it will be held against rotation but has limited oscillation by reason of the engagement of the slots 18^a and the heads of the screws 19^a, renders the valve self-adjusting, thereby not only permitting a greater tolerance of dimensions in the machining of the parts, but, in addition, insuring against unequal wear upon the valve during operation. The spherical configuration of the upper surfaces of the valve also provides a very efficient safeguard against binding or seizing of the bearing surfaces of the spindle 22 and valve member even though the entire weight of the motor armature and the action of the spring 48 forces these two surfaces together with a considerable pressure.

In this connection the provision of the means for circulating a lubricant under pressure to the upper end of the valve member is also important, because, as hereinbefore pointed out, the film of lubricant maintained between the spherical surface forms a very effective cushion to take up the end thrust. Although the upper surface of the valve member and the inner surface of the bore 23 have been shown and described as being of spherical configuration it will be understood that the invention is not limited to a spherical configuration of such surfaces but that they can be conical, ellipsoidal, paraboloidal, plate shaped, or any other shape; the principal requirement being that these surfaces have a contacting surface area extending transversely to the axis of rotation of sufficient extent to act as an efficient thrust bearing. For the purpose of rendering the self-adjustment of the valve and the bore of the spindle more efficiently self-adjusting the lower portion of the cylindrical side wall of the valve is cut away as indicated by the reference character 90, so that the bearing surfaces of the valve and bore terminate approximately at the lower end of the spherical surface of the bore 23.

With respect to the lubricating system it will be seen that with the present invention the lubricant contained in the compartment 13 automatically serves to perform the following important functions: First, the carrying off of the heat of compression by conduction and circulation. Second, the silencing of the operation. Third, the lubrication and cooling of the main bearing 46 by directing onto and through it a copious stream of cooling lubricant under pressure. Fourth, acts as a cushion for end thrust upon the valve member 18. Fifth, provides pressure lubrication for said valves. Sixth, lubricates by

contact the pistons 27, piston pin 31 and rollers 30. Seventh, provides a seal against gas or oil leakage about the periphery of the valve member 18. Eighth, provides a seal against leakage past the pistons, due to the fact that the cylinder block rotating at high speed acts as a rotary pump for the lubricant in compartment 13 and sets up, by centrifugal force, a pressure in the body of lubricant in excess of the pressure of compression, and Ninth, by contacting both with the exterior and interior of the hollow pistons effectively cools them. As the compartment 13 is substantially filled with oil, a sufficient supply is provided so that refilling is unnecessary during a long period of operation and furthermore no attention is necessary for lubricating or oiling any of the moving parts except to replenish the oil in the compartment 13 at comparatively long intervals. During the operation the pistons 27 are lubricated solely by the dipping contacting of the pistons with the oil at the outer end of the piston skirts, oil being carried inwardly toward the center of rotation, by the wiping action of the piston and capillarity, to a sufficient extent to insure complete lubrication of the entire length of the cylinders. The centrifugal force due to the rapid rotation of the cylinders makes the accumulation of any excess oil in the cylinder heads impossible and therefore prevents the passage of any appreciable amount of oil into the air or other fluid being pumped by the compressor. Proper lubrication of the rollers 30 and pins 31 is rendered more certain by proportioning the projecting ends of the pins 35 relatively to the grooves 37 so as to insure that as the pistons reciprocate, said pin ends and said grooves will function as small pistons and cylinders to produce a pulsating effect upon the lubricant in the grooves and force it through the conduits 77, 78 and oil groove 79.

While I have described the compartment 13 as being filled with oil it will be understood that the term "oil" has been used merely for convenience and not in a limiting sense; obviously any suitable liquid having lubricating qualities and the property of acting to conduct heat to the casing walls may be used. Owing to the heat conduction from the pistons and cylinders to the casing walls by the lubricating fluid and furthermore due to the extra radiating surface provided by the conical inner ends of the cylinders and pistons, isothermal compression is more closely approached than with a compressor having flat ended cylinders and pistons and consequently the efficiency of the compressor is greatly increased.

Again while it is preferable to provide a sealed lubricant filled chamber in which the cylinders and pistons rotate, the use of such chamber is not absolutely essential as it will be obvious that the race 33 could be mounted upon a fixed spider or other suitable skeleton

support and air cooling of the cylinders employed.

During the rotation of the cylinders as the pistons are moving outwardly on suction strokes the angular velocity of the piston rollers is increasing while on the compression stroke their velocity decreases, kinetic energy will therefore be stored up on the suction stroke which increases the available power for the compression strokes.

As the suction strokes are performed while the pistons are moving outwardly and as the fluid being pumped is admitted approximately at the axis of rotation, the rotation of the cylinders will tend to set up a centrifugal force in the incoming fluid and consequently the cylinders will be completely filled with fluid on suction strokes thereby attaining maximum volumetric efficiency.

While I have disclosed the rotating cylinder block as being mounted upon a central spindle, it will be understood that the spindle and cylinder block could be made as a single casting. The construction illustrated however is preferred because when an equal number of cylinders are provided, as shown, the boring of two diametrically opposite cylinders can be performed in one operation.

It will be noted that the valve 18 has its intake and discharge conduits both connecting with conduits in the stationary casing at the same end of the axis of rotation. This is a very important advantage because it not only simplifies the construction considerably over one in which the intake and outlet conduits are at opposite ends of the axis of rotation but in addition renders it possible much more efficiently to seal the compressor against leakage about the valve can be sealed merely by pressure exerted towards that end of the casing through which the conduits of the valve connect with the conduits of the casing, the pressure for insuring the sealing of the contacting meeting faces of the valve and the casing being provided by the spring 48.

The pressure of the spring 48 in addition to insuring the sealing of the meeting faces of the valve and casing, also serves in co-operation with the nested spherical surfaces of the spindle 22 and valve member to cause the latter to perform a steadyng function somewhat similar to a lathe center even though the valve has a limited degree of free movement which renders it self-adjusting. The sealing of the meeting faces of the valve and casing, as just described and the provision of the packing members 47, 49 and 50 makes the compressor well adapted for use with refrigerating installations or for pumping any dangerous gases. Moreover, the danger of gas leakage is reduced to a minimum by operating the cylinders and pistons in a fluid tight chamber containing a body of oil, the centrifugal forces due to the rotation of the cylinders maintaining the oil at the circum-

ferential wall of the compartment 13 so as to form an effective liquid seal, and at the same time said centrifugal forces tend to build up a pressure in the liquid, which being greater than the compression pressure, 5 enables the liquid also to prevent gas leakage outwardly between the pistons and cylinder walls.

In order to guard against the building up 10 of oil under pressure between the contacting bearing surfaces of the valve member 18 and the disc 19, and to guard against the leakage of oil between said surfaces and the passage of such oil into the delivery conduits 16, the 15 upper face of the disc 19 is provided with a circular oil groove 91, arranged in spaced concentric relationship about the oil conduit 73. On that side of its circumference nearest to the conduits 16, the groove 91 communicates with a second groove 92 which, as clearly shown in Fig. 12, surrounds the conduits 16 in spaced concentric relationship thereto. Means are provided for permitting the escape 20 of oil entering the grooves 91, 92 into the interior of the compartment 13. Such means may consist of a groove such as the small groove 93, which communicates at the outer edge of the disc 19 with the compartment 13 and which at its inner end communicates 25 with the groove 92. The particular shape and location of what may be termed the transverse groove 93, obviously can be varied, for example, such groove could run substantially diametrically across the disc so as to communicate with both grooves 91 and 92.

When the compressor is constructed in 30 larger sizes for capacities beyond certain limits, or when smaller sizes are subjected to such severe operating or service conditions that there will be a tendency for it to heat up unduly, I contemplate the use of a radiating coil arranged exteriorly of the compartment 13, which coil will communicate at one end with the compartment 13 near the periphery thereof at a high pressure zone of the oil contents and which coil at its other end will communicate with said compartment 35 pressure nearer to the axis of rotation at a low pressure zone. The oil within the compartment will therefore be circulated through the radiating coil to be cooled in its passage therethrough and then returned to the compartment 13.

While I have shown and described herein 40 a satisfactory constructional example of my invention, it will be understood that the principles of the invention are not limited to the constructional details illustrated, but that many changes, variations and modifications 45 may be made without departing from the spirit of the invention. For example, although the cylinders 24 and pistons 27 have been shown as extending radially from the axis of rotation, it will be perfectly obvious 50 that the invention is not limited to a construc-

tion in which the longitudinal center lines of the pistons and cylinders coincide with radii having their centers at the axis of rotation. Therefore, the expression "radially arranged cylinders" or similar expressions contained 55 in the claims appended hereto is not to be construed as limiting the invention to the specific arrangement of the cylinders shown but is entitled to refer to a construction in which the cylinders are grouped about a central 60 axis of rotation whether radially to such axis, partly to radii extending from said axis or inclined to such radii.

I claim:

1. An air compressor of the type wherein a 65 plurality of radially arranged cylinders each provided with a port at the inner end thereof is rotatable about a central valve member provided with inlet and discharge ports with which the cylinder ports are brought into 70 communication alternately by the rotation characterized by said valve member being provided with an intake conduit and a discharge conduit terminating at one end respectively in alignment with said inlet and discharge 75 ports, both of said conduits extending lengthwise of the axis of rotation and terminating at their other ends at the same end of said axis of rotation.

2. An air compressor of the type wherein a 80 plurality of radially arranged cylinders each provided with a port at the inner end thereof is rotatable about a central valve member provided with inlet and discharge ports with which the cylinder ports are brought into 85 communication alternately by the rotation characterized by said valve member being provided with an intake conduit and a discharge conduit terminating at one end respectively in alignment with said inlet and discharge 90 ports, both of said conduits extending lengthwise of the axis of rotation and terminating at their other ends at the same end of said axis of rotation.

3. A compressor as set forth in claim 2 in 95 which the rotating cylinders and valve member are provided with co-operating bearing surfaces arranged in nested relationship and inclined to the axis of rotation, and means for urging said surfaces towards each other with a yielding pressure whereby the valve member 100 will be self-adjusting.

4. In an air compressor, a cylinder having a conical end at the apex of which a port is provided, a piston slidably mounted in said cylinder and having one end thereof of conical shape similar to that of said cylinder, 110 means to produce relative reciprocation between said cylinder and piston, and a valve member adjacent to said port and intersecting a portion of the conical end of said cylinder for controlling the alternate ingress 115 and egress of fluid to said cylinder, the conical shapes of the ends of said cylinder and piston and the intersection of said valve member with said cylinder insuring the elimination of dead air pockets and reducing the 120

clearance volume to an irreducible minimum.

5. An air compressor of the type wherein a plurality of radially arranged cylinders each provided with a port at the inner end thereof is rotatable about a central valve member provided with inlet and discharge ports with which the cylinder ports are brought into communication alternately by the rotation characterized by said cylinders forming part of an integral structure having a central bearing surface extending transversely to the axis of rotation thereof, said valve member having a bearing surface similar to said first named surface; means to force said bearing surfaces towards each other with a yielding pressure, and said valve member being further provided with an oil hole terminating at the center of said bearing surfaces, means to force a lubricant under pressure through said oil hole and an oil groove encircling said oil hole, whereby an area of lubricant under pressure is provided adjacent to the center of said bearing surfaces.
25. 6. A compressor as set forth in claim 5 in which a radial oil channel connects with said oil groove and terminates outside of said bearing surfaces for permitting escape of excess oil.
30. 7. A compressor as set forth in claim 5 in which said oil groove is provided in the central bearing of the rotating cylinder structure whereby excess of oil is forced into said oil groove by centrifugal force.
35. 8. A compressor comprising a central rotatable driving shaft, and a bearing therefor, a plurality of radial cylinders secured to said shaft, a fluid tight casing in which said cylinders are mounted, said casing containing a liquid having high heat conducting and lubricating properties, an oil conduit leading from said casing in the high pressure region of said liquid produced by centrifugal forces, said oil conduit terminating at said bearing and a return connection from said bearing to said casing and terminating in a low pressure region of the latter.
50. 9. A compressor comprising a central rotatable driving shaft, a plurality of radially extending cylinders secured to said shaft, a fluid tight casing in which said cylinders rotate, a valve member located at the inner ends of said cylinders, said cylinders and valve member being provided with co-operating bearing surfaces, an oil conduit leading from a high pressure region of said casing to said bearing surfaces and a return connection from said surfaces to a low pressure region of said casing.
55. 10. A compressor as set forth in claim 8 in which a valve member is located at the inner end of said cylinders, said cylinders and valve members being provided with co-operating bearing surfaces, an oil conduit leads from the high pressure region of said

casing to said bearing surfaces, and a return connection extends from said surfaces to a low pressure region of said casing.

11. A compressor as set forth in claim 8 in which a valve member is located at the inner end of said cylinders, said cylinders and valve members being provided with co-operating bearing surfaces, an oil conduit leads from the high pressure region of said casing to said bearing surfaces, and a return connection extends from said surfaces to a low pressure region of said casing, and means are provided for controlling the rate of flow of lubricating liquid through said last named conduit.

12. A compressor comprising a pair of casing members secured together adjacent to their peripheries and defining a substantially cylindrical compartment, a plurality of spaced radially extending cylinders mounted for rotation in said compartment and a liquid contained in said compartment, said liquid being rotated by the rotation of said cylinders at an angular velocity sufficient to cause a pressure in excess of the compression pressure to be set up in said compartment at the outer circumferential wall thereof whereby said liquid will act as a seal to prevent leakage of the fluid, pumped by said compressor, between the meeting joint of said casing members.

13. A compressor comprising a plurality of cylinders equally spaced about a common axis of rotation and extending radially therefrom, a piston mounted for reciprocation in each of said cylinders, a two-part fluid tight casing in which said cylinders are mounted, and a circular race fixed within said casing at the meeting joint of said two part casing and eccentrically of said axis, and means carried by said pistons for engagement with said race, said race serving as a gasket for said meeting joint and also to cause said pistons to perform their compression strokes.

14. A compressor comprising a plurality of cylinders, rotatable about a common axis of rotation, and extending radially thereto, a piston slidably mounted in each cylinder, a circular race secured to a fixed support eccentrically of said axis, and anti-friction means carried by said pistons for engagement with said race, said race serving to cause said pistons to move inwardly of said cylinders to perform their compression strokes and said pistons being moved outwardly towards said race solely by the centrifugal forces due to the rotation of said cylinders.

15. A compressor as set forth in claim 14 in which the anti-friction means and said race are provided with interengaging parts for preventing rotation of said pistons about their own axes.

16. A compressor comprising a plurality of pistons rotatable about a common axis in a fluid tight lubricant filled casing, a circular

- race secured to said casing eccentrically of said axis, a piston mounted for reciprocation in each cylinder and having a roller for engagement with said race, a pin carried by 5 each piston upon which its respective roller is rotatably mounted each said cylinder and piston being provided one with a longitudinally extending channel and the other with a projection protruding into said channel, and 10 each said pin having an oil conduit communicating at one end with said channel and terminating at the other end at the bearing surfaces of said pin and roller, whereby, during reciprocation of said piston, lubricant within 15 said channel will be impelled by said projection into and through said oil conduit to said bearing surfaces.
17. A compressor as set forth in claim 13 in which said race has circular outer and inner 20 faces eccentric to each other, the outer face being seated within a circular support eccentric to the axis of rotation of said cylinders whereby rotary adjustment of said race within said support will vary the effective eccentricity of said race relatively to the axis of rotation of said cylinders.
18. A compressor as set forth in claim 13 in which said race has circular outer and inner faces eccentric to each other, the outer 25 face being seated within a circular support eccentric to the axis of rotation of said cylinders whereby rotary adjustment of said race within said support will vary the effective eccentricity of said race relatively to the axis of rotation of said cylinders and means for 30 producing rotary adjustment of said race.
19. In a compressor, a cylinder having a conical head and a port at the apex thereof, a valve having a ported spherical surface located at said apex and a piston slidably mounted in said cylinder and having a conical head that fits exactly the conical head of said cylinder, and the conical head of said piston being truncated by the intersection of a 35 sphere of the same diameter as the spherical surface of said valve whereby all valve pockets are eliminated and clearance space is reduced to an irreducible minimum.
20. In a compressor, a driving shaft, a 40 driven shaft, a coupling connecting said shafts in torque transmitting relationship and preventing relative axial movement between said shafts, a casing having a bearing concentrically surrounding said driven shaft in spaced relationship thereto, said driven shaft having a laterally projecting flange or shoulder defining with said bearing a pocket, an antifriction bearing member in said pocket, a spring bearing against said bearing 45 member to hold it against said flange and a plurality of members, including a packing gasket, for retaining said spring in position and defining a stuffing box for said casing.
21. An air compressor of the type where- 50 in a plurality of rotating cylinders each hav-
- ing a piston mounted for reciprocation therein is grouped about a central valve member and means are provided for rotating said cylinders, characterized by said cylinders and pistons being mounted within a sealed lubricant containing chamber and said valve member being mounted for limited self-adjusting movement upon a bearing plate, a lubricating conduit extending through said valve member and bearing plate and communicating with said chamber near the outer walls thereof, a circular oil groove surrounding said conduit and a second oil groove extending from said circular groove and communicating with said compartment near the center thereof.
22. In a compressor, a plurality of cylinders and pistons rotatable in a closed lubricant containing chamber, a pair of spaced axially aligned bearings upon which said cylinders rotate, conduits leading from said chamber adjacent to the outer walls thereof to said bearings, connections leading from said bearings to said compartment adjacent to the center thereof, a mass of resilient porous material extending across one of said conduits and means to adjustably compress said mass of material thereby to vary the effective porosity thereof and control the rate of flow of the lubricant through said one conduit.
23. A compressor comprising a fluid tight chamber, a plurality of cylinders each having a piston mounted for reciprocation therein enclosed within said chamber, inlet and discharge conduits adapted to be placed in communication with said cylinders passing through said chamber but normally out of communication therewith, said chamber being provided with but a single aperture, driving means passing through said aperture and a fluid tight stuffing box surrounding said driving means adjacent to said aperture whereby if leakage of the fluid pumped by said compressor should occur from said cylinders or conduits escape thereof from said chamber will be prevented.
24. A compressor comprising a plurality of cylinders rotatable about a common axis, each of said cylinders having a piston slidably mounted therein, means for producing relative reciprocation between said cylinders and pistons, including a central driving shaft upon which said cylinders are mounted, a casing enclosing said cylinders and pistons having an extended exposed, radiating surface, and means for drawing a current of cooling air across said surface comprising a fan mounted on said driving shaft and deflecting means for causing the air currents produced by the rotation of said fan to sweep across substantially the entire area of said radiating surface.
25. A compressor, a set forth in claim 24, in which an electric motor is employed as a prime mover and is connected with the central

driving shaft, and deflecting means is provided with a central aperture surrounding said driving shaft, said fan and deflecting means causing the cooling current of air to be forced through the electric motor and drawn across the radiating surface of the compressor, whereby the air propelled by said fan produces a cooling effect upon both the motor and compressor.

10 In testimony whereof I have hereunto set my hand.

WALTER H. RUDOLPH.
